THERMOSTAT

Victor Weber, Greensburg, Pa., assignor to
 Robertshaw Thermostat Company, Youngwood,
 Pa., a corporation of Pennsylvania

Application April 15, 1942, Serial No. 439,149

2 Claims. (Cl. 236—48)

This invention relates to thermostat mechanisms and, more particularly, to those of the multi-lever snap-acting type.

An object of the invention is to permit manufacture and testing of the snap-acting mechanisms as complete units apart from the thermostat proper to assure uniform and accurate adjustment before assembly.

Another object of the invention is to reduce the space required for the assembly by permitting offset arrangement of the parts while retaining positive action thereof.

Another object of the invention is to render the device simple and compact and adapted for rapid assembly and relatively inexpensive to manufacture.

Other objects and advantages will become apparent from the following description taken in connection with the accompanying drawing, wherein:

Fig. I is a cross-section through a control body showing the operating mechanism and valve in plan;

Fig. II is a longitudinal section taken on line II—II of Fig. I;

Fig. III is a section taken on the line III—III of Fig. I;

Fig. IV is a section taken on the line IV—IV of Fig. II;

Fig. V is a section taken on the line V—V of Fig. II;

Figs. VI to IX are perspective views of parts of the lever mechanism.

Referring more particularly to the drawing, the control body 10 is generally rectangular in form, having substantially the same width and thickness but of greater length, and is provided with an auxiliary portion 12 on one side thereof of less length than the main control body 10. The main body 10 is open on the side opposite the auxiliary portion 12 and is provided with a closure plate 14 secured thereto by means of the screws 16. The open side of the body 10 does not extend for the full length of the body but terminates short of one end thereof leaving a flange 18. An outlet 20 is provided in the end of the body 10 adjacent the flange 18 and may be threaded or otherwise adapted for connection with a pipe leading to the burner of the appliance with which the control is to be used.

The auxiliary portion 12 is separated in part from the interior of the main body 10 by a partition 22 which extends lengthwise of the body 10 and is provided with a recess 24 having a bottom wall 26 and a side wall 28. The side wall

28 has an opening 30 therethrough providing access between the recess 24 and a valve chamber 32 formed by the space between the partition side wall 28 and the outer wall of the auxiliary portion 12.

The valve chamber 32 contains a valve member 34 adapted to seat against the side wall 28 and control passage of fluid through the opening 30. The valve member 34 is yieldably retained on its seat by means of a coil spring 36 extending between the valve member 34 and a cap 38 threadedly engaging with an opening in the outer wall of the auxiliary portion 12 and providing access to the valve member when the cap 38 is removed. A stem 40 projects from the valve member into a stem guide 42 projecting from the cap 38 and the valve member may further be provided with a projection 44 extending opposite the valve stem 40 through the opening 30 and into the recess 24.

That portion of the auxiliary body 12 separated from the main body 10 by the bottom wall 26 of the partition forms an inlet chamber 46 with which a pair of angularly disposed inlet openings 48 communicate. The inlet openings 48 may be threaded or otherwise adapted for connection with pipes leading from a source of fuel supply. It will be apparent that only one such inlet 48 could be provided and only one is required to be chosen for connection purposes but greater flexibility in installation is provided by the arrangement described. Due to the provision of the partition 22 which, as stated, extends throughout the length of the body 10, the only path of communication between the inlet 48 and outlet 20 is from the chamber 46 through the opening 30, controlled by the valve member 34, and into the recess 24 to the interior of the main body 10, with which the outlet 20 communicates.

The burner of the appliance which receives fuel from the outlet 20 operates in response to a thermostat carried by a boss 50 projecting from the main body 10 on the side opposite the cap 38. The thermostat shown is of the rod-and-tube type, such as may be inserted in the storage tank of a water heating system with which the burner is associated. The tube 52 of the thermostat of this embodiment has a high coefficient of expansion and is mounted at its inner end in a threaded opening 54 of the boss 50. The rod 53 of the thermostat, which may be of invar or other material having a low coefficient of expansion, extends within the tube 52 and abuts 55 a plug 56 threaded or otherwise secured in the

end of the tube 52. The opposite end of the rod 56 abuts one end of a pin 60 which is slideable in the wall of the main body 10 and projects into the interior thereof. The rod 56 is supported in the tube 52 by spaced projections 61 extending into slideable engagement with the interior surface of the tube.

The thermostat is adapted to operate, upon cooling of the water in the storage tank of the water heater, by movement of the rod 56 to the right from the position shown in Fig. III, due to contraction of the tube 52, which opens the valve 34 through the interposition of suitable multi-lever snap-acting mechanism. Conversely, when the temperature in the storage tank increases, the tube 52 expands, permitting the rod 56 to move toward the left to the position shown in Fig. III, causing movement of the valve member 34 to closed position through the same snap-acting means.

The multi-lever snap-acting mechanism of this invention is entirely self-contained and may be assembled and tested apart from the control body 10. The mechanism comprises a frame 62, upon which all of the levers are mounted, and which has opposite arms 64 connected at one end of the frame by a tubular element 66. The element 66 is adapted for engagement at its opposite ends with a pair of pivots 68 carried by the flange 18 and the opposite side wall of the body 10, respectively. The arms 64 are also connected by a back portion 70 which may be integral with the arms 64 and extends from the end opposite the tubular element 66 and terminates short of this element. The portion 70 is provided with a flange 72 extending between the arms 64 at the end opposite the tubular element 66 and being provided with a notched portion 74 forming a fulcrum seat for a thermostat lever 76. The flange 72 is retained against displacement from its position between the arms 64 by short projections 78 formed on the arms 64 and overlying part of the flange 72 for this purpose.

The pivots 68 which engage with the tubular element 66 of the frame are preferably in the form of screws having threaded engagement with the control body 10 and being adjustable from the exterior thereof. In this manner, the pivots 68 may readily be removed from engagement with the tubular element 66 and upon removal of the closure plate 14, the frame 62 and associated parts may be removed as a unit from the control body. Furthermore, such arrangement permits adjustment of the frame 62 and the levers associated therewith on the pivots 68 from exterior of the control body 10. For this purpose, the side of the control body 10 opposite the boss 50 is provided with an additional boss 78 which may be hollow and have projecting therethrough a threaded adjusting pin 80 which can be moved into and out of engagement with the frame portion 70 by an adjusting handle or dial 82.

The dial 82 may be fastened to the pin 80 by means of a headed screw 84 having its threaded end inserted in an axial hole in the pin 80, there being a coil spring 86 extending between the underside of the dial 82 and the bottom of the hollow boss 78. The dial preferably carries a pointer 88 which cooperates with suitable indicia marked on the surface of the control body 10 to indicate the temperature setting of the device.

The snap-acting leverage carried by the frame 64 comprises three principal parts. The thermostat lever 76, as previously mentioned, has a fulcrum seat in the notched portion 74 of the flange

72 carried by the frame 62. This lever 76 is channel-shaped and has part of its base removed, leaving an opening at the central portion thereof with spaced bar portions 89 and 91 respectively at each end connected by arms 93 at the sides.

5 The bar portion 89 has its outer edge seated in the fulcrum seat 74 of the frame 62 as previously mentioned, a knife-edge bearing being provided on this edge. Operative engagement of the lever 10 76 with the thermostat is provided by a stem 90 having a rounded end seated in a depression 92 formed in the central portion of bar 89 of lever 76 and having its opposite end abutting the pin 60. The pin 90 is slidably mounted in a bearing portion 94 carried by the depending arm 96 of an angular stop plate 98 which is secured by means of the screws 100 to the flange 72 of the frame.

15 The width between the arms 93 of the thermostat lever 76 is sufficiently less than that between the arms 64 of the frame 62 to provide a space for the accommodation of the arms 102 of a valve operating lever 104. These arms 102 are connected at their upper portion by a bar 106 extending between the thermostat lever 76 and arm 96 of the stop plate. The bar 106 has a recessed portion 108 centrally disposed on its underside and a depressed bearing portion 110 on the opposite side, the purpose of which will appear hereinafter. A valve operating arm 112 projects laterally from the bar portion 106 across one arm 20 64 of the frame 62. The operating arm 112 is of sufficient length to project into the recess 24 of the auxiliary body portion 12 when the parts are assembled in the control body and carries a tip 114 which engages with the projection 44 of the valve member 34.

25 The bar portion 91 constituting the free end of the thermostat lever 76 is provided with a depressed bearing portion 116 similar to the bearing portion 110 and adapted to accommodate one hook end 118 of a coil spring 120, the other hook end 122 of which engages with the bearing portion 110 of the lever 104. The spaced ends of the arms 102 of the valve operating lever 104 are 30 provided with suitable knife-edge bearing portions 124 which are received within fulcrum seats 126 formed on the arms 128 of a channel-shaped support 130. The support 130 is pivotally mounted on the arms 64 of the frame 62 by the provision of notched bearings 132 formed on the arms 64 adjacent the tubular element 66 and providing support for the opposite ends of a pin 134 35 extending between the arms 128 of the support 130. In order to prevent the thermostat lever 76 from displacement, a limit stop pin 136 may project from the channel-shaped support 130 into the path of movement of the lever 76.

40 A tail-piece 138 may extend from the base of the channel-shaped support 130 and project at an angle thereto in the opposite direction to the arms 128. The tail-piece 138 carries a screw 140 which can be adjusted to bear against the tubular element 66 and, by changing the position of fulcrum seat 126 relative to that of fulcrum seat 45 14, serve to change the tension of the spring 120 within limits as desired. Movement of the valve operating lever 104 may be limited by the provision of a depending finger 142 formed on the depending arm 96 of angular stop plate 94 and 50 projecting into the path of movement of the lever 104.

55 In the operation of the device described and shown, the parts will assume the positions shown in the drawing Figs. I to IV when the temperature of the water in the storage tank has reached 75

that for which the dial 82 has been set. When the tube 52 of the thermostat becomes cold due to cooling of the water in the storage tank, the rod 56 moves to the right, exerting pressure upon the lever 76 to move it in a counter-clockwise direction about its fulcrum seat 74. Sufficient movement of the lever 76 in this direction will carry the end 118 of the spring 120 far enough to the right of the fulcrum seat 126 to enable the spring to exert sufficient force upon the valve operating lever 104, to move it to the right with a snap action to open the valve 32. After the tube 52 has again become sufficiently heated, the pressure of the rod 56 on the thermostat lever 76 is relieved sufficiently to permit movement of this lever in a clockwise direction, returning the end 118 of the spring 122 to its original position and permitting the spring 120 to move the valve operating lever 104 to the left with a snap action and permitting the valve 34 to close.

By adjusting the dial 82 to move the end of the pin 80 toward or away from the frame 62 the position of the frame 62 and therefore the position of the thermostat lever 76 may be varied with respect to the rod 56 of the thermostat to set the temperature at which the mechanism will operate. The adjusting dial 82 engages the frame 62 intermediate the pivots 68 and the stem 90 of the thermostat. Thus, any looseness which develops in the pivotal mounting will not affect the accuracy of the adjustment as might be the case if the mounting were otherwise arranged with respect to the dial and thermostat.

The device lends itself readily to assembly of the snap-acting mechanism in considerable quantities and testing thereof in a single test body. When the snap-acting mechanism has been thus tested and its operation checked in the test body, it can be assembled in final position in any standard control body with the assurance that further testing will be unnecessary. Considerable space is conserved by the provision of the offset arrangement of the valve with respect to the thermostat while retaining the positive snap-acting operation of the valve. It will be understood that various changes may be made in the construction and arrangement of the parts as described and shown herein without departing from the spirit and scope of the invention as defined in the appended claims.

I claim:

1. Snap-acting thermostat mechanism comprising a main body having a fluid passage, an auxiliary body disposed at one side of said main body and having a fluid passage, a valve member reciprocable in said auxiliary body and controlling communication between said passages, a frame pivotally mounted at one end thereof in said main body, valve actuating means carried

5 by said frame and comprising a thermostat lever having one end fulcrumed on the end of said frame opposite the pivotal mounting, a support fulcrumed on said frame at the end opposite said thermostat lever, an operating lever fulcrumed at one end on said support and extending toward the fulcrumed end of said thermostat lever, a tension spring connecting said levers, an operating arm projecting laterally from said operating 10 lever for operative engagement with said valve member, means adapted for axial movement relative to said actuating means and being engageable with said thermostat lever adjacent the fulcrumed end thereof, said axially movable means being responsive to thermostatic operation for causing movement of said valve member by snap-action of said actuating means, limit stop means extending into the path of said levers for retaining said actuating means in said frame, and adjusting means 15 carried by said main body and engageable with a portion of said frame intermediate the pivotal mounting and the plane of said axially movable means for varying the position of said actuating means relative to said axially movable means.

2. Snap-acting thermostat mechanism comprising a main body having a fluid passage, an auxiliary body disposed at one side of said main body and having a fluid passage, a valve member reciprocable in said auxiliary body and controlling communication between said passages, a frame pivotally mounted at one end thereof in said main body, valve actuating means carried by said frame and comprising a thermostat lever having one end fulcrumed on the end of said frame opposite the pivotal mounting, a support fulcrumed on said frame at the end opposite said thermostat lever, an operating lever fulcrumed at one end on said support and extending toward the fulcrumed end of said thermostat lever, a tension spring connecting said levers, an operating arm projecting laterally from said operating lever for operative engagement with said valve member, pin means engageable with said thermostat lever adjacent the fulcrumed end thereof and being responsive to thermostatic operation for causing movement of said valve member by snap-action of said actuating means, a limit stop carried by said frame and extending into the path of said operating lever, said limit stop having an aperture through which a portion of said pin means slidably extends, a second limit stop carried by said support and projecting into the path of said thermostat lever, said limit stops cooperating to retain said actuating means in said frame, and 30 adjusting means carried by said main body and engageable with said frame for varying the position of said actuating means relative to said pin means.

VICTOR WEBER.
